UNITED STATES PATENT OFFICE.

SAMUEL S. GROSJEAN, OF NEW ORLEANS, LOUISIANA.

STERILIZER.

1,098,570.

Specification of Letters Patent. Patented June 2, 1914.

Application filed January 23, 1914. Serial No. 813,879.

To all whom it may concern:

Be it known that I, SAMUEL S. GROSJEAN, a citizen of the United States, residing at New Orleans, in the parish of Orleans and State of Louisiana, have invented certain new and useful Improvements in Sterilizers, of which the following is a specification.

This invention relates to sterilizing apparatus for dental and surgical tools, and other articles or appliances, characterized by a chamber containing a sterilizing liquid and a tray, on which latter the appliances to be sterilized are placed, said tray being slidably for immersing the appliances in the sterilizing liquid.

It is the object of the present invention to provide the chamber with a closure in the form of a hinged lid which is operatively connected to the tray in such a manner that the tray is lowered when the lid is swung closed, and raised when the lid is swung open.

This object is attained by means of a novel combination and arrangement of parts to be hereinafter described and claimed, reference being had to the accompanying drawings, in which—

Figure 1 is a perspective view of the apparatus; Fig. 2 is a central longitudinal section thereof on the line 2—2 of Fig. 1; Fig. 3 is a cross-section; Fig. 4 is a horizontal section on the line 4—4 of Fig. 3; and Fig 5 is a perspective view of one of the tray supporting members.

Referring specifically to the drawings, the sterilizing chamber 10 may be of any desired shape and dimensions, the same being mounted on a base 11 supporting a gas-burner 12 which extends lengthwise beneath the bottom of the chamber. The chamber 10 is provided with a closure in the form of a hinged lid 13 having on its under side a continuous depending flange 14 which latter fits snugly in the top portion of the chamber when the lid is closed, thus making a tight closure. A tray 15 for supporting the appliance to be sterilized is slidably mounted in the chamber 10, said tray having a perforated bottom 16 to freely admit the sterilizing liquid when the tray is lowered thereinto. On the end walls of the chamber 10, inside the same, are mounted vertical strips 17 having inturned marginal flanges 18 which are spaced to form undercut vertical slide-ways, in which latter are mounted slides 19

having at the bottom a shelf 20 for supporting the tray 15, the latter being removably supported at its ends on the shelves. As the slides which carry the shelves are free to move up and down in the slideways, it will be evident that the tray may be raised or lowered in the chamber upon operating the slides.

In order that the tray 15 may move simultaneously with the lid 13, the slides 19 have outstanding studs 21 on their outer faces, near the top, which studs are engageable by curved arms 22 extending from the under side of the lid and passing under the studs. These arms are located at the ends of the lid, and they are secured to the flange 14, near the hinged portion of the lid. The curvature of the arms is such that when the lid is swung down to close the chamber 10, the slides travel downward and allow the tray 15 to lower into the sterilizing liquid, whereas, when the lid is swung open, the slides are carried upward by the arms, and the tray rises out of the sterilizing liquid. The operation of raising and lowering the tray is therefore automatically effected by the swing of the lid.

One end of the lid 13 carries a pivoted prop 23 for holding the same in open position, said prop being engageable with the top of one of the strips 17 for this purpose when the lid is open. On the end wall of the chamber 10 is a guide and retaining bar 24 under which the prop works.

The apparatus herein described is very simple and inexpensive in construction, and it effectually serves the purpose for which it is designed.

The preferred embodiment of the invention has been shown, but it will be understood that various changes in the structural details illustrated may be made without departure from the spirit and scope of the invention as claimed hereinafter.

I claim:

1. The combination with a sterilizing chamber having a hinged closure and internal vertical slideways on opposite walls, slides mounted in the slideways, a tray in the chamber supported by the slides, and a connection between the closure and the slides for raising and lowering the latter by the movement of the closure.

2. The combination with a sterilizing chamber having a hinged closure, of slides

mounted in the chamber on opposite walls thereof, said slides having outstanding studs, a tray in the chamber supported by the slides, and curved arms carried by the closure and extending beneath the studs for raising and lowering the slides by the movement of the closure.

In testimony whereof I affix my signature in presence of two witnesses.

SAMUEL S. GROSJEAN.
